UNITED STATES PATENT OFFICE

2,322,999

ROAD GRADER

Franklin E. Arndt, Galion, Ohio, assignor to The Galion Iron Works & Manufacturing Company, a corporation of Ohio

Original application March 12, 1940, Serial No. 323,586. Divided and this application April 29, 1941, Serial No. 390,952

14 Claims. (Cl. 37—156)

My invention relates to a road grader, and one of its objects is the provision of improved and efficient circle mechanism for carrying the grader blade and adjusting the inclination of the latter relative to the path of travel of the machine.

Other objects of the invention will appear hereinafter, the novel features and combinations being set forth in the appended claims.

This case is a division of my co-pending application S. N. 323,586, filed March 12, 1940.

In the accompanying drawings,

Figs. 1 and 2, placed end to end, show a side elevation of the road grader embodying my improvements;

Fig. 3 is a bottom plan view of the circle mounted on the rear end of the T-shaped drawbar;

Fig. 4 is a sectional elevational view taken on the line 4—4 of Fig. 3, looking in the direction of the arrows; and

Fig. 5 is a sectional view taken on the line 5—5 of Fig. 3, looking in the direction of the arrows.

As shown in Fig. 2, the main supporting frame 15 is upwardly arched and is supported at its rear end on its wheels 16 and at its front end on the wheels 17 (Fig. 1). The frame 15 comprises spaced-apart longitudinal side beams, and as shown in Fig. 2 these spaced-apart side beams are connected by the tubular cross braces 19, 20 and 21.

The machine shown in the accompanying drawings includes mechanism for the steering of the front wheels, the leaning of the front wheels, the leaning of the rear wheels, the shifting of the rear end of the main frame laterally relatively to the rear wheels, the shifting of the moldboard laterally and movement thereof to bank sloping position, and the adjustment and locking of the circle shown in Fig. 3. All of the controls extend to a single operator's station or platform 22 at the rear end of the machine, as shown in Fig. 2. Although I have shown in the accompanying drawings a pull type of road working machine comprising a tongue 23 to the front end of which is adapted to be connected a pulling tractor, it should be understood that my improvements hereinafter described are also useful in a power grader comprising a power plant, connected to the rear traction wheels for moving the entire machine along the roadway.

The front wheel steering mechanism comprises a driving sprocket 24 meshing with a chain 25, the ends of which are connected by

means of links 26 to the bolster 28 mounted on the front axle. The bolster 28 has surmounted thereon a cap 42 which has a central opening in its top. It will thus be seen that the bolster 28 and the front axle-tree 40, 41 form a single rigid structure for supporting on the wheels 17 the front end of the vehicle frame 15.

The tubular tongue 23 has rigidly secured to the rear end thereof a vertical plate 43. A tube 44 is secured as by welding to the rear end of the plate 43, and plates 45, 46 are welded to the lower and upper edges of the plate 43 and the lower and upper ends of the tube 44. The plates 45 and 46 are provided with openings which register with openings in the cup bearing 47 and the bracket bearing 48. The cup bearing 47 is secured to the upper horizontal flange of the angle iron 40. The bracket bearing 48 is secured rigidly to the cap 42 of the bolster 28. A bearing rod 49 may be dropped through the bracket bearing 48, the opening in the plate 45, the tube 44, and the opening in the plate 46 with the lower end of the rod 49 in the cup bearing 47. The rod 49 may then be pinned to the bracket bearing 48.

When the steering wheel 53 at the rear of the machine (Fig. 2) is rotated, the shaft 54 will transmit rotary motion through the universal joints 55, 56, 57 and the links 58, 59 to the worm gearing in the casing 60 and thus rotate the sprocket 24 meshing with the chain 25 and thereby swing the tongue 23 in one direction or the other relatively to the front wheels. A counterbalancing spring 61 is connected to the tongue 23 intermediate its ends and also to a swiveled connection 62 at the top of the post 59, as shown in Fig. 1.

The drawbar 81 as shown in Figs. 1 and 2, comprises a narrow elongated front end 82 connected by an intermediate curved portion to a rear horizontal T-shaped frame which carries the circle 83. As shown in Fig. 3, the drawbar may comprise two angle irons 84, 84 welded together with their horizontal flanges at the bottom so that a plate 85 may be welded along the upper edges of the angle irons and slotted at its forward end portion to slide down over and be welded to the vertical legs of the angle irons.

The front end of the drawbar is provided with a universal connection 90 to the steering post 50. The lower end of the steering post 50 is provided with a plate which is adapted to rest on a circular support at the upper end of the cap 42 as shown in Fig. 1. The drawbar 81 may turn on its swiveled connection at 90 relatively to the steer-

ing post 50 and moreover the drawbar 81 may swing laterally upon an upright axis. Furthermore, the drawbar 81 may swing up and down.

It should be particularly noted that the steering post 50 is rigidly connected to the forward ends of the channel beams 18 of the vehicle frame 15. The universal connection 90 at the forward end of the drawbar 81 is therefore in reality connected to the front end of the main frame and the parts are so closely related that no relative vibration between them is possible irrespective of the various high lift grading positions to which the grader blade has been adjusted.

The circle 83, as shown in Figs. 2 and 3, carries the moldboard 97 by means of the arms 98. Mounted on the cross-piece 99 at the rear end of the drawbar are circumferentially spaced retaining plates 100, 101 as shown in the bottom plan view of Fig. 3. Abutments 102, 103 are welded to the bottom of the cross-piece 99. Slotted wedge plates 104, 105 are located between the abutment plates 102, 103 and slidably abutment plates 106 located on top of the plates 100 and 101. Fig. 5 is a sectional view taken on the line 5-5 of Fig. 3.

The plates 100 and 101 are in fixed relation to the cross-piece 99 when the bolts 107, 107' are tightened in place. The plates 100, 101 are adapted to overlap the flange 108 of the circle but the latter is free to slide along these plates 100 and 101 when the circle rotating mechanism is operated. The plates 106 have enlarged openings for the bolts 107, so that they may engage the inner edges of the flange 108 of the circle. This is effected by means of the wedges 104, 105 which engage the inner edges of the plates 106 when the bolts 107 are loosened. That is to say, when the bolts 109, 109 are loosened as well as the bolts 107, 107', the wedges 104, 105 may be moved tangentially of the center of the circle along the abutments 102, 103, thereby forcing the outer edges of the plates 106 against the inner edges of the flange 108. After this has been done the bolts may be re-tightened.

The rotatable circle carries a segmental arcuate rack 110 with which meshes the pinion 111 as shown in Fig. 3. The pinion 111 is connected to the lower end of a shaft, the upper end of which is connected by means of worm gearing through the link mechanism 112, gearing 113 and a flexible shaft 114 to the gear mechanism in the casing 115 for actuation by means of a lever when the latter is set in a predetermined position. This mechanism operated by a lever may be such as that illustrated in the patent to Arndt, No. 2,012,463, granted Aug. 27, 1935, for an improvement in road planer or drag.

Mechanism for locking the circle in adjusted position comprises a pawl 116 which is pivotally mounted on the drawbar frame members 84, 84 for up and down pivotal movement on the axis 117 shown in Fig. 4. An arm 118 extends from the pawl 116 into position for connection by means of a restoring spring 119 to the bracket 120.

The casting 121 is provided with journal bearings 122 for the transverse shaft 117. An arcuate extension 123 underlaps the flange 108 as shown in Fig. 4. An abutment plate 106' engages the cylindrical abutment surface 124 at the inner edge of the circle 83 adjacent the flange 108. It will thus be seen that the abutment plates 106, 106, 106' engage the inner edge or cylindrical abutment surface 124 of the flange 108 so as to properly hold the circle for circular adjustment in fixed relation to the T-shaped drawbar. The

bracket casting 121 as well as the abutment plate 106' are provided with registering openings for receiving the bolts 125, 125. As shown in Fig. 7 the abutment plate 106' extends circumferentially beyond the lateral edges of the bar comprising the bottom flanges 84, 84. The retaining plate 123 underlaps the bottom annular retaining flange 108. The width of the retaining plate 123 equals the width of the said bar, as shown in Fig. 7. The bolts 125, 125 each fits in registering openings in the flanges 84, 84, the abutment plate 106' and the retaining plate 123. Therefore when these bolts are tightened the plates 106' and 123 are rigidly secured to the flanges 84, 84. Consequently, the bolts 125, 125 may be left tightened and the wedges 104, 105 relied on to adjust the abutment plates 106, 106' while moving the flange 108 against the abutment plate 106' which is held stationary relative to the drawbar by the bolts 125, 125. In other words, the abutment plate 106' is in fixed relation to the drawbar while the other two abutment plates 106, 106' are each adjustable radially relative to the cross-piece of the drawbar. In each instance, however, bolts serve to clamp the retaining plates to the abutment plates in fixed positions relative to the drawbar. After adjustment of the circle has been made with respect to the T-shaped drawbar, the bolts are re-tightened so as to hold the plates 106, 106, 106' in close fitting relation to the cylindrical abutment surface 124 with the retaining plates 100, 101 and 123 underlapping the flange 108. Inasmuch as Fig. 3 is a bottom plan view, it can readily be seen that the circle when in adjusted position is supported from the T-supported drawbar by means of the retaining plates 100, 101 and 123 which are extended under the flange 108.

The spring 119 acts on the arm 118 to move the toothed pawl 116 into mesh with the arcuate rack 110, as shown in Figs. 3 and 4. By pulling the handle 126 at the operator's station (Fig. 2), the links 127, 128 may be actuated so as to move the bell crank 129 on its pivot 130 and thereby exert a forward pull on the link 131 which is connected to the upper end of the lever 118. In this manner the pawl 116 is pulled down and released from the arcuate rack 110.

While the operator holds the pawl 116 released by pulling on the handle 126 he may adjust the actuating lever into such position as to enable him to operate the links 132, 133 so as to secure transmission through the gearing 113 by actuation of the worm gearing in the casing 114 and thus effect rotation of the pinion 111 to in turn rotate the circle 83. In this manner the operator at his station may swing the moldboard 97 to a desired angle relative to the path of travel of the machine, while the moldboard remains under the machine as shown in Fig. 2, in road grading position.

As shown in Figs. 3 and 4, the lower side of the latch pawl 116 is provided with a web plate which spans the spaces between the teeth of this latch pawl in positions to engage the lower ends of the teeth of the rack bar 110 and thus act as abutments to limit the upward movement of the pawl 116 when released and acted on by the spring 119. Since this abutment mechanism is mounted on the under side of the drawbar it serves to assure desirable meshing between the teeth of the pawl 116 and the teeth 110 of the circle so that whenever desired by the operator, the pawl may be easily released manually from the arcuate rack 110.

The pawl 116 is pivotally connected to the underside of the drawbar for support thereby and has a plurality of teeth adapted to mesh with the teeth of the arcuate rack 110. The pinion 111 meshes with the same rack 110 and only when the pawl 116 is released can the pinion 111 be rotated to effect rotation of the circle 83. That is to say, the latch pawl may be operated to lock or release the circle and the teeth of this latch pawl engage the same rack that serves in the rotation of the circle.

It should also be noted that the arcuate rack 110 is inwardly facing and that the latch pawl 116 is pivotally mounted within the periphery of the circle 83 and that it is spring-pressed to resiliently bias it toward locking position with its teeth meshing with some of the teeth of the arcuate rack. The operator at his station 22 may by pulling the handle 126 unlock the pawl latch 116 by swinging it vertically downward to free the circle for turning relatively to the drawbar by rotation of the pinion 111.

The moldboard may be adjusted in elevation and in inclination transversely of the roadway by means of structure comprising the crank arm 155 and the extensible hangers 135, one located on one side of the machine and the other located on the opposite side of the machine.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. A road grader drawbar comprising an integral bar inverted T-shaped in cross-section and having a rear horizontal portion and a front horizontal portion connected by a curved intermediate portion, the front portion being at a higher elevation than the rear portion, a flat plate extending along the top of said bar and slotted at its forward end to receive the vertical flange of the bar, the slotted portion of said top plate being bent down to the horizontal flanges of the bar and welded to the sides of said vertical flange of the bar, and means for mounting a circle on the rear horizontal portion of the bar.

2. A road grader comprising a drawbar, a circle for carrying a moldboard, an arcuate rack on said circle and concentric therewith, a latch pivotally connected to the underside of said drawbar for support thereby and having a plurality of teeth adapted to mesh with teeth of the said arcuate rack, means for swinging said latch into and out of locking engagement with said rack, a pinion meshing with said rack, and means for rotating said pinion to rotate the circle together with the moldboard thereon when said latch is released from said rack.

3. In a road grader, the combination with a drawbar comprising a longitudinal bar and branching supports, of a moldboard carrier mounted on said longitudinal bar and said branching supports for arcuate adjustment relative thereto, an arcuate rack on said carrier, mechanism mounted on said longitudinal bar and comprising a pinion meshing with said rack to effect adjustment of the moldboard carrier relative to said drawbar, a toothed latch pawl pivotally mounted on the under side of said

longitudinal bar adjacent said pinion in position to mesh with said rack when swung upwardly, and means for operating said latch pawl to apply or release the same, said pawl when applied to said rack locking said carrier against rotation relatively to said drawbar and thereby preventing rotation of said pinion.

4. In a road grader, the combination with a drawbar, of a circle having an arcuate retaining surface on its under side, mechanism comprising a retaining plate secured to said drawbar for supporting said circle for arcuate adjustment relative to said drawbar, an arcuate rack on said circle, a latch pawl pivoted to said retaining plate in position to be moved upwardly against the action of gravity into engagement with the said arcuate rack to lock the circle against arcuate movement, spring actuated mechanism for holding said latch pawl in its locking position, and manual mechanism for releasing said latch pawl against the action of said spring actuated mechanism.

5. A road grader comprising a T-shaped drawbar including a longitudinal bar with a cross-piece at its rear end, a circle for supporting a moldboard, an annular flange on said circle with an annular retaining face on its under side in the plane of the circle and a cylindrical abutment face concentric with said circle, three circumferentially spaced retaining plates one connected to said bar and the other two connected to said cross-piece, three abutment plates one connected to said bar and the other two to said cross-piece, said abutment plates being in position to engage said cylindrical abutment face and the abutment plate connected to the bar being in fixed relation thereto while the other two abutment plates are adjustable relative to the cross-piece, and means for clamping the retaining plates to the abutment plates to hold the latter and said retaining plates in fixed positions relative to the bar and cross-piece.

6. A road grader comprising the combination with a drawbar, of a circle mounted thereon and adapted to carry a moldboard, an arcuate rack on said circle, a latch pawl, means pivotally supporting said latch pawl on the underside of said drawbar in position to swing upwardly into engagement with teeth of said rack bar to lock the circle against turning relatively to said drawbar, resilient means for biasing said latch pawl into locking position, and mechanism for unlocking said latch pawl by swinging the same downwardly to free said circle for turning relatively to said drawbar.

7. A road grader drawbar comprising a rear horizontal portion and a forward horizontal portion connected by an intermediate curved portion, the forward and intermediate portions having a vertical flange to form an inverted T-shape in cross-section, circle carrying and guiding mechanism on the rear horizontal portion, and a flat plate extending along the top of the said vertical flange and slotted at its forward end to receive such vertical flange, such flat plate at its forward slotted portion being secured to said inverted T-shaped portion.

8. A road grader drawbar comprising a bar inverted T-shaped in cross section and having a rear horizontal portion and a front horizontal portion connected by a curved intermediate portion, the front portion being at a higher elevation than the rear portion and having its vertical flange cut away on a slant toward the forward end of the bar, a flat plate extending along

the top of the bar and slotted at its forward end to receive the vertical flange of the bar, the slotted portion of the top plate being bent down to the horizontal flanges of the bar and secured to the latter to provide slanting of the slotted portion in conformance with the slant of said cutaway portion of the vertical flange of the bar, and means for mounting a circle on the rear horizontal portion of the bar.

9. In a road grader, the combination with a drawbar having a cross-piece at its rear end, of a circle for supporting a moldboard, an annular flange on said circle with an annular retaining face on its under side and a cylindrical abutment face concentric with said circle, a plurality of circumferentially spaced detachable retaining plates each in position to underlap said annular flange and engage the retaining face thereof, abutment plates between said cross-piece and said retaining plates, and bolts fitting in circular holes in said retaining plates and extending through slots in said abutment plates, said bolts when tightened holding said abutment plates in adjusted positions relative to said cylindrical abutment face and securing all of said plates to said cross-piece.

10. In a road grader, the combination with a drawbar, of a circle connected to said drawbar for supporting a moldboard, an annular flange on said circle with an annular retaining face on its under side and a cylindrical abutment face concentric with said circle, a plurality of circumferentially spaced retaining plates each in position to underlap said annular flange and engage the retaining face thereof, abutment plates between said drawbar and said retaining plates, abutment blocks secured to said drawbar and spaced from said abutment plates, wedges slideable along said abutment blocks and slideable along said abutment plates for moving the latter against said cylindrical abutment face, means for securing said wedges in adjusted positions, and bolts fitting in holes in said retaining plates and extending through said drawbar and through slots in said abutment plates.

11. A road grader comprising the combination with a drawbar, of a moldboard carrier mounted thereon for arcuate adjustment relative thereto, an arcuate rack on said carrier concentric with said arcuate adjustment, mechanism mounted on said drawbar and comprising a pinion meshing with said rack to effect such arcuate adjustment of the moldboard carrier relative to said drawbar, a toothed latch pawl pivotally mounted on the under side of said drawbar in position to swing upwardly into mesh with said arcuate

rack, and means for operating said latch pawl to apply or release the same, said pawl when applied to said arcuate rack locking the carrier against rotation relatively to said drawbar and thereby preventing rotation of said pinion.

12. A road grader comprising the combination with a T-shaped drawbar including a longitudinal bar connected to laterally branching supports, of a circle for carrying a moldboard, an inner circular flange on said circle and having an annular retaining surface on its under side in the plane of the circle and a circular abutment surface facing inwardly, circumferentially spaced retaining plates in position to extend under said flange to engage said annular retaining surface, movable abutment plates between said retaining plates and the drawbar, abutments fixed to said laterally branching supports, manually operable wedges between said fixed abutments and said movable abutment plates for moving the latter against said circular abutment surface, vertical bolts for securing said wedges in adjusted positions, and vertical bolts for securing said retaining plates and abutment plates rigidly to the drawbar.

13. A road grader comprising a drawbar, a circle mounted thereon for arcuate adjustment relative thereto and adapted to carry a moldboard, an inwardly facing arcuate rack on said circle, means connected to said rack to rotate the circle, a latch pawl having a plurality of teeth with the spaces between the same closed on the bottom to form webs adapted to engage teeth of said rack to limit upward movement of the pawl, means for pivotally supporting said latch pawl on said drawbar within the periphery of said circle for vertical swinging movement of its teeth into and out of engagement with said rack, and means for operating said latch pawl, said latch pawl being adapted to engage the same rack that serves in the rotation of said circle.

14. A road grader comprising the combination with a drawbar, of a circle mounted thereon for arcuate adjustment relative thereto and adapted to carry a moldboard, an arcuate rack on said circle, means connected to said rack to rotate the circle, a toothed latch pawl pivotally mounted on said drawbar to swing downwardly, relatively thereto, abutment mechanism for limiting the upward swing of said pawl when in position to mesh with said rack, and means for operating said toothed latch pawl, said latch pawl being adapted to engage the same rack that serves in the rotation of the circle.

FRANKLIN E. ARNDT.
